ABSTRACT

Apparatus for controlling the amount of elastic stretch in stretch woolens having a cylindrical drum rotatably mounted on a stand. A drive roll is supported by arms pivotally mounted on vertical members which extend upwardly from the stand and there is a piston mecha-

nism for moving the drive roll into rolling contact with the cylindrical surface of the drum. A drag roll is also supported by arms mounted on vertical members which extend upwardly from the stand and the drag roll is positioned adjacent the drive roll with their axes of rotation being parallel to each other. A drive mechanism connected to the drive roll causes the cylindrical drum to rotate and results in the fabric being passed therearound and between the drum and the drive roll. The rotational speed of the drag roll is maintained slower than that of the driving roll to produce a stretch in the warp yarns of the fabric. The amount of stretch applied to these warp yarns is varied by mechanically controlling the rotational speed of the drag roll. Primary steam conduit structure is partially mounted within the cylindrical drum with the section within said drum having a plurality of apertures in its outer wall that allows the steam to be released within said drum. This steam in turn escapes from the drum through a multitude of apertures in its cylindrical surface and then passes through the fabric which is travelling around the drum. A secondary steam conduit structure is also partially mounted within the cylindrical drum with its internal portion being in the form of a helical coil which acts to prevent condensation in the drum of the steam released therein by the primary steam conduit structure. An auxiliary bath is mounted on the stand in a position to receive the fabric after it has passed around the drive roll. Squeeze rolls are supported on the stand in a position to receive the fabric after it has been passed through the bath. By varying the amount of drag by the drag roll, the amount of permanent elastic stretch to be imparted into the woolen fabric passing through the apparatus can be varied as the permanent set is produced by the action of the steam passing through the chemically impregnated fabric.

APPARATUS FOR CONTROLLING THE AMOUNT OF ELASTIC STRETCH IN STRETCH WOOLENS

BACKGROUND OF THE INVENTION

The invention relates to apparatus for controlling the amount of elastic stretch permanently set into stretch woolens. In the past the creases or pleats formed on treated wool fabrics by a steam press or by steaming between pleating papers has been found not to be stable. They disappeared gradually during normal wear and were lost immediately if wetted with water. The set imparted to stretched fibers and wool fabrics creased or pleated in this manner was called "cohesive" or "temporary set." Since strained, temporarily set wool fibers and fabrics are not firmly held, they tend to assume their unstrained configuration when water enters them and the crease or pleat is then completely lost.

It has been found, however, that when strained wool fibers are treated with boiling water or steam for an extended period of time they acquire a set which is stable or "permanent" to subsequent wetting, even with hot water. In this case the degree of set is dependent on the time of boiling or steaming. When alkalies or reducing agents are added to the boiling water or steam the rate of permanent setting has been found to increase very rapidly.

With this knowledge available industry has proceeded to produce what is known as stretch woolens by impregnating wool fabric with an aqueous solution of monoethanolamine sulfite and then squeezing the fabric in open width to give a final wet pickup of 60 to 80 percent by weight of the dry fabric. Next having a knowledge of the amount of stretch which is desired to be imparted to the fabric, the fabric was then placed in tension warpwise which reduced the width of the fabric. This particular section of the fabric which is now under the predetermined tension was then steamed for the required period of time in order to give a permanent set to the strained wool fibers. In the past this has been a slow process since only a limited amount of the fabric could be properly stretched out and then steamed at a time due to the physical limitations of the equipment used at that time. In many cases this meant that a given length of the fabric had to be cut from the roll in order to be placed in the necessary stretched condition and this length was governed by the length of the equipment in which the steaming took place.

The stretch woolens are primarily produced as a fabric to be used in outer garments for men's and women's wear and they impart to these garments improved characteristics in both appearance and comfort. The elastic effect of garments made from such material makes them more comfortable and they may be made more form fitting as they accommodate themselves to bodily movements. The stretch woolen fabrics have a very high tailorability also. Garments made from this fabric remain smooth in appearance as any wrinkles are removed by the elastic pull back of the fabric. Trousers retain their crease for long periods for the same reason. Additionally, the garments do not tend to wrinkle or pucker at the seams in moist weather as in the case of the usual woolen fabrics which absorb moisture and shrink when wet.

SUMMARY OF THE INVENTION

The operation of applicant's apparatus for control-

ling the amount of elastic stretch permanently imparted to stretch woolens will be quickly comprehended. A preliminary step necessary for the apparatus requires that the woven woolen fabric first have been impregnated with an aqueous solution of monoethanolamine sulfite. Starting at this point the fabric is threaded first over and partially around the drag roll, then almost completely around the cylindrical surface of the steam decator drum during which the fabric passes beneath a driving roll that is positioned in rolling contact with the steam decator drum and finally back around a portion of the drive roll. At this point the fabric may be passed next into a bath or directly through the squeeze rolls. The drive roll is rotated at a speed greater than the speed of rotation of the drag roll to place a tension warpwise upon the warp yarns. This increased stretching of the warp yarns causes the weft yarns to pull up and to have an increased crimp amplitude as they pass over and under successive transverse warp yarns. By varying the amount of difference between the speed of rotation of the drive roll and the drag roll, the amount of elastic stretch to be imparted to the fabric may be controlled. As the fabric is passing around the rotating decator drum steam is passed into the drum which escapes outwardly through the apertures in the cylindrical surface of the drum and passes through the fabric thereby imparting a permanent set to the yarn in its stretched and distorted condition. The time cycle for the fabric to rotate around the drum is predetermined to be at least the minimum amount of time which is necessary for the steaming operation to give a permanent set to the warp and weft yarns of the fabric. During the steaming process the chemicals that had been impregnated into the fabric in the aqueous solution rearrange the molecular chains of the wool fiber permanently setting the crimp of the filling yarn.

DESCRIPTION OF THE DRAWINGS

FIG. 1 is a left side elevation view of applicant's apparatus for controlling the amount of elastic stretch in stretch woolens;

FIG. 3 is a plan view of applicant's apparatus with the drive mechanism for the drive roll and the drag roll not shown;

FIG. 3 is a partial elevation view illustrating the decator drum and the steam conduit structures partly in cross section;

FIG. 4 is a schematic elevation view illustrating the manner in which the drive roll and drag roll have their rotation controlled;

FIG. 5 is a plan view showing the fabric as woven and prior to the shrinking operation;

FIG. 6 is a section taken on line 6-6 of FIG. 5;

FIG. 7 is a plan view similar to FIG. 5 showing the fabric in finished contracted form; and

FIG. 8 is a section taken on line 8-8 of FIG. 7.

DESCRIPTION OF THE PREFERRED EMBODIMENT

Referring to FIGS. 1 and 2 of the drawings applicant's apparatus for controlling the amount of stretch in stretch woolens is generally designated by the numeral 10. The woven woolen fabric which is to be preconditioned before it is passed therethrough. When it is ready for threading into the apparatus, the fabric has already been impregnated with an aqueous solution of mono-

ethanolamine sulfite followed by a squeezing operation to provide it with the proper amount of wetness.

The preconditioned fabric **W** is first threaded over guide roller **12** then beneath guide bar **14** and next over guide roller **16**. These guide members have their ends secured to laterally spaced arms **18** which extend outwardly at 90° angles to vertical members **20**. The vertical members **20** form a portion of stand **17**. Next the fabric is directed downwardly around guide bar **22** and upwardly over and partially around drag roll **30**.

Guide bar **22** is part of tensioning mechanism **21** that is secured to vertical members **20**. The mechanism **21** has a shaft **23** with a worm gear **24** mounted on one end and a wheel **25** mounted on the other end for adjusting the tension on the fabric. Rotation of wheel **25** causes gear **24** to rotate pinion gear **26** mounted on shaft **27**. This causes the tension bar **28** having its opposite ends connected to arms **29** to increase or lower the tension of bar **28** against the fabric as the arms are rotated upwardly and downwardly.

Screw bar **31** over which the fabric **W** passes on the way to drag roll **30** functions to spread the cloth out evenly before it passes on to drag roll **30**. Both the drag roll **30** and screw bar **31** are supported at their opposite ends by arms **35** having one of their ends secured to vertical members **38**. The fabric passes around drag roll **30** and then onto the cylindrical surface of decator drum **40**. As the fabric passing around the drum reaches the top of the drum it passes between drive roll **50** and steam decator drum **40** which are in rolling contact. It is drive roll **50** which rotates the drum causing the fabric to be passed therearound it. After the fabric passes over and partially around the drive roll **50** it has the option of being passed through the bath **60** and then through squeeze rolls **70** or may go directly to squeeze rolls **70** and bypass the bath. Drive roll **50** has its opposite ends mounted on laterally spaced arms **51** one of whose ends are pivotally secured on vertical members **52** by shaft **53**.

When it is desired to thread the fabric under drive roll **50**, a switch (not shown) is actuated to pass air through tube **54** into cylinder **55**. This causes the piston rod **56** connected to a piston within the cylinder to raise arm **51** away from the cylindrical surface of drum **40**. After the fabric has been threaded thereunder a second signal releases air through tube **57** into cylinder **55** causing the piston rod to draw drive roll **50** back into rolling engagement with drum **40** with the fabric pinched therebetween. The lower end of cylinder **55** is pivotally secured to bracket **58** mounted on cross member **59**. The cross members in turn are supported by legs **61** with this general support structure of the apparatus also forming a part of the stand **17**.

If the fabric is to be passed through bath **60**, it initially passes over guide roll **62** down into the liquid within the bath and around roll **63** which holds the fabric down in the bath and then upwardly over guide roll **64**. Spray pipes **65** are mounted above the path to provide a constant supply of liquid within the bath. The fabric then is passed between the squeeze rolls **70**.

In operation as the fabric is passing around the decator drum **40**, steam is being supplied to the inside of the drum and allowed to escape through apertures **42** in the cylindrical surface of the drum. This is best illustrated by referring to FIG. 3. The drum has closed end walls **41** each having a neck **43** extending outwardly therefrom. The opposite ends of the drum are sup-

ported on roller bearings **44** that are supported on the top of legs **45**. Primary steam conduit **46** has its horizontal section **47** journaled within the neck sections **43** of the drum. This allows the drum to rotate while the horizontal section **47** remains stationary. Steam supplied from a source is directed inwardly through steam conduit **48** and it passes through apertures into the interior of the drum. The steam then escapes through apertures **42** and passes through the fabric traveling around the drum. It is this steaming which sets up the permanent set of the crimps of the warp and weft yarns. A second steam conduit **49** passes into the interior of drum **40** through steam conduit **48**. The portion of the steam conduit **49** within the drum is formed in the shape of a helical coil and it functions as a super heater to prevent condensation of the steam released through apertures **48** of the first steam conduit. A steam hood is mounted over said steam drum to provide a chimney through which excess steam may be vented out of the work area.

The fabric according to this invention is shown in FIGS. 5-8 as composed of warp yarns **80** and weft yarns **90**. FIGS. 5 and 6 show a fabric as woven prior to shrinkage. In this form the yarns are spaced apart a sufficient distance to provide clearance for the shrinkage to which the fabric is subjected. In the embodiment shown the fabric is woven with a plain weave wherein the warp yarns **80** are substantially straight and the weft yarns **90** are crimped as they pass under and over successive warp yarns.

The finished fabric after being shrunken is illustrated in FIGS. 7 and 8 wherein it will be noted that the warp and weft yarns are more closely spaced than the fabric of FIGS. 5 and 6 and the weft yarns **90** are more highly crimped, that is, there are more crimps per inch due to the greater number of warp yarns per inch in the contracted state of the fabric and they are bent more sharply as they pass under and over the successive warp yarns.

The manner in which the method of controlling the amount of elastic stretch in stretch woolen fabrics will be most easily understood by referring to FIGS. 4-8. In FIG. 4 a schematic illustration shows the major components of applicant's novel apparatus, the steam decator drum **40**, drag roll **30** and drive roll **50**. Drive roll **50** is connected by chains and sprockets to motor **72** which is a variable speed motor. Rotation of drive roll **50** causes drum **40** to rotate and convey the fabric through the apparatus as described previously. Drag roll **30** in a similar manner is connected by chains and sprockets to motor **74** which is also of the variable speed variety. It is to be realized that by the exercise of ordinary mechanical skill both rolls could have their rotation controlled by a single motor and still function in the same manner.

By having the drive roll rotate at a faster rate of speed than that of the drag roll the warp yarns of the fabric are caused to elongate and remove some of their crimp from their length. At the same time the weft yarns have their length shortened, and this causes the crimp in the weft yarns to increase in amplitude as the yarn is pulled up and bent more sharply as it traverses first over and then under successive warp yarns. The high shrinkage results in increasing the number of yarns per inch and thereby produces a denser fabric. The crimp is increased in frequency due to the increased number of yarns per inch and in amplitude as the yarns are pulled

up and bent more sharply in their traverse. This increased density up-grades the fabric and improves its appearance and value by an amount greatly in excess of the processing cost.

The process also provides for stabilizing the fabric in this highly compacted and crimped state. This stabilization imparts a memory to the yarn so that when it is thereafter deformed it tends to return to its original state. The fabric is highly stretchable weftwise due to the fact that when it is tensioned, the crimp is pulled out of the yarns although the yarns do not themselves increase in actual length. When the stretching force is removed, the yarn memory causes the yarns to pull back and the crimp to be restored. The pull-back effect is equivalent to that normally produced by rubber yarns but in this case is produced by the memory effect of the wool yarn. By varying the degree of difference between the speed rotation of the drive roll and the drag roll the amount of stretch which is permanently set into the fabric by the steaming operation can be varied. For example, if there is only a small difference between the speed of the two rolls, the amount of elastic stretch permanently set into the wool fabric will be relatively small. Likewise a greater difference between their two rotational speeds will produce a greater amount of elastic stretch permanently set in to the fabric. Tension gauges or stretch meters may also be utilized to maintain quality control over the degree of elasticity permanently set into the fabric.

What is claimed is:

1. Apparatus for controlling the amount of weftwise elastic stretch in stretch woolens comprising a cylindrical drum having closed ends and a multitude of spaced apertures along its cylindrical surface, shaft means extending from the opposite ends of said drum, bearing means rotatably supporting said shaft means, primary steam conduit means mounted partially within said cylindrical drum and adapted to be connected to a source of steam outside said drum, the section of said primary steam conduit means within said drum having a plurality of apertures in its

45

outer wall that allows steam to be released within said drum which steam then escapes out of the drum through the multitude of apertures in its cylindrical surface and passes through a fabric traveling around said drum, secondary steam conduit means mounted partially within said cylindrical drum and adapted to be connected to a source of steam outside said drum whereby said secondary steam means acts to prevent condensation in the drum of the steam released therein by said primary steam conduit means,

a stand,

a drive roll supported by said stand near said drum and on the woolen removal side of the drum having means for rotationally driving it, means for moving said drive roll into rolling contact with said drum whereby rotation of said drive roll causes said drum to rotate and feed a fabric around said drum, a drag roll supported by said stand on the woolen feeding side of said drum,

means for varying the rotational speed of said drag roll with respect to the rotational speed of said drive roll.

2. Apparatus for controlling the amount of elastic stretch in stretch woolens as recited in claim 1 wherein said means for moving said drive roll into contact with said drum comprises a cylinder, a reciprocating piston therein, and a piston rod having one of its ends attached to said piston.

3. Apparatus for controlling the amount of elastic stretch in stretch woolens as recited in claim 1 wherein said drive roll and drag roll are mounted adjacent each other near the top of said cylindrical drum.

4. Apparatus for controlling the amount of elastic stretch in stretch woolens as recited in claim 1 further comprising a steam hood supported over the top of said drum.

5. Apparatus for controlling the amount of elastic stretch in stretch woolens as recited in claim 1 wherein the portion of said second steam conduit means within the cylindrical drums is in the shape of a helical coil.
